UNITED STATES PATENT OFFICE

2,190,682

DIRECTION OF ROTATION RESPONSIVE
SWITCH

Howard Avery Satterlee, Needham, Mass., assignor to Submarine Signal Company, Boston, Mass., a corporation of Maine

Application November 17, 1936, Serial No. 111,272

3 Claims. (Cl. 200—1)

The present invention is a continuation in part of applicant's prior application, Serial No. 1,032, filed January 9, 1935, and entitled "Method and apparatus for the measurement of rotational velocities," now Patent No. 2,088,613, dated August 3, 1937.

The present invention relates to the indication of the direction of rotation of a rotating shaft and to apparatus for performing a switching operation whenever the shaft reverses its direction of rotation.

In the above mentioned application I have described a method and apparatus for measuring and indicating the velocity of a rotating shaft. The system described in that application makes possible a substantially instantaneous indication of the shaft's speed produced by means of a stationary index.

The present invention provides a device whereby an indication of the direction of rotation of a rotating shaft can automatically be obtained and furthermore whereby any desired switching operation when the shaft reverses its direction of rotation may be effected.

My invention will best be understood by consideration of the following description and of the accompanying drawing in which Figure 1 shows a perspective view of a simple form of the invention and Figure 2 shows a modification of Figure 1.

As shown in Figure 1, 19 indicates the shaft whose speed is to be measured. This shaft is geared by suitable gearing 17, 18 to an auxiliary shaft 15. The shaft 15 consequently reverses its direction whenever the shaft 19 reverses its direction. Mounted on the shaft 15 is a rotary contact element 20 having a conducting segment 37 with which cooperate pairs of brushes 27 and 28. When the conducting segment 37 passes under either of these pairs of brushes, the brushes of that pair are short-circuited. If the brushes be included in an electrical circuit, the circuit must be closed for a brief period of time.

Now for the purpose of selecting one or the other of the sets of brushes 27 or 28 or for the purpose of closing or opening any desired electrical circuit when the shaft reverses its direction of rotation a special device is provided in accordance with the present invention. This device includes a friction collar 21 which comprises two blocks of wood 29 held against the shaft by means of a phosphor bronze spring member 30 with just sufficient force when the shaft rotates to produce a small torque on the spring member

so that its lower end 31 which carries the contact 32 will be moved to the left or to the right.

When the contact 32 is moved to the left, it makes contact with the stationary contact 33. Thus, when the shaft is rotating in one direction, i. e., clockwise, the contacts 32, 33 will be closed while, when the shaft rotates counter-clockwise, the contacts will be open. The contacts 32, 33 may be connected in circuit with an electromagnet 34 of the relay 35 and energized from any suitable power source. The relay 35 may, for example, be provided with any desired number of armatures, for example, 45 and 48. When the magnet 34 is not energized, the armature 45 is held against contact 46 while at the same time the armature 48 is held against contact 49. On the other hand, when the electromagnet 34 is energized by the closing of the contacts 32, 33 the armature 45 is held against the contact 44 and the armature 48 is held against contact 47.

If the armature 45 and contact 46 are connected as shown to form the ends of a series circuit including the indicating lamp 36 and a source of power, the lamp 36 will be illuminated for one direction of rotation of the shaft and extinguished for the reverse direction of rotation. Likewise, another lamp connected in series with the source of power to contact 44 and armature 45 will indicate by its illumination the reverse direction of rotation. In a similar manner, the armature 48 and the contacts 47 and 49 may, as shown, be connected to the brushes 27 and 28 on the contact element 20 whereby one or the other set of brushes is automatically selected for one or the other direction of rotation of the shaft. The brushes 27 and 28 may be employed in my speed measuring system described in my above mentioned copending application or may be employed for any other desired purpose.

In the modification of Fig. 2 only the auxiliary shaft 15 has been shown. On the shaft are mounted two metal face plates 50 and 51 by means of screws 52, 53 respectively. Bearing against these plates and loosely mounted on the shaft are the discs 54 and 55 respectively which may conveniently be made of wood. These blocks are held in frictional engagement with the respective plates by means of the spring 56. Slots 57 and 58 are cut in the discs 54 and 55 respectively into which fit the ends of a rod 59 which is at its center supported by the lever 60. The latter is in turn supported at 61 by the rod 62 which is mounted by the bearings 63 and 64 in vertical projections 65 and 66 of a frame member 67. The lever 60 is firmly fixed to the shafts 59 and 55.

and 62 so that the latter turns with the lever. The lever 60 is provided at its upper end with a slot 68 which engages a bar 69. The latter by means of a longitudinal slot 70 engages the ends 5 of any desired number of movable switch members 71, 72, 73, 74. The latter carry contacts adapted to cooperate with a lower set of contacts 15 to 18 and with an upper set of contacts 18 to 22. At the ends of the rods 62 are mounted 10 sets of brushes 83 and 84 which cooperate with the rotary contact elements 85 and 86 respectively. The latter are provided with conducting segments 87 and 88. The lower end of the lever 60 terminates in a right-angle portion 89. Beneath the end of the portion 89 there is mounted 15 on the frame 67 a U-shaped element 90 having the adjusting screws 91 and 92. When the shaft 15 rotates in one direction, say, counter-clockwise, the friction between the plates 50, 51 and 20 the discs 54, 55 tends to rotate the latter in a counter-clockwise direction. The rod 59 whose ends are engaged in the slots 57, 58 likewise tends to rotate in the same direction. Such rotation is limited, however, by the abutment of the portion 89 of the lever 60 against the screw 91 as 25 shown in Fig. 2.

Similarly when the shaft 15 rotates in the opposite or clockwise direction the discs 54, 55 rotate in this direction until element 89 strikes the 30 screw 92. The motion of the lever 60, when the shaft 15 reverses its direction in this manner, causes its forked end to bring about the raising of the bar 69 thereby causing the movable switch members 71 to 74 inclusive to leave the lower contacts 75 to 78 inclusive and make contact with the upper contacts 79 to 82 inclusive. This motion of the lever 60 likewise causes the rotation of the rod 62 so that the brushes 83 are removed 35 from the contact element 85 while the brushes 84 are brought to bear against the contact element 86.

Similarly to Fig. 1, the direction of rotation signals may be connected to one of the sets of contacts 78, 79, 80 if desired and the impulse 40 transmitting circuits for use in the system described in the above mentioned copending application may be connected to brushes 83 and 84 or alternatively any desired circuits may be energized or de-energized as required.

Having now described my invention, what I claim is:

1. Apparatus responsive to the direction of rotation of a shaft including, in combination, a pair of rotary contact elements secured to said shaft, 5 two sets of brushes cooperating with said contact elements respectively and means frictionally actuated by motion of said shaft for removing one set of brushes from contact with its contact element and placing the other set of brushes in contact with its contact element whenever the shaft reverses its direction of motion.

2. Apparatus responsive to the direction of rotation of a shaft including, in combination, a pair of abutments secured to the shaft, a spring, a 15 pair of friction discs mounted on said shaft so as to be rotatable with respect thereto and urged against said abutments by said spring, a plurality of contact means, a lever mechanism operated by partial rotation of said friction discs and 20 thereby operating the said contact means, a pair of rotary contact elements also secured to said shaft, two sets of brushes cooperating with said contact elements respectively and means actuated by said lever mechanism for removing one 25 set of brushes from contact with its contact element and placing the other set of brushes in contact with its contact element whenever the shaft reverses its direction of motion and simultaneously with the operation of said first contact 30 means.

3. Direction of rotation-responsive switch including, in combination, a shaft, a pair of abutments secured to said shaft spaced a short distance apart, a pair of friction discs surrounding 35 said shaft, one of said discs frictionally engaging each of said abutments, a spiral spring around said shaft between said discs, thereby pressing each disc against its corresponding abutment, a bar extending parallel to the axis of said shaft into apertures in said discs, a pivoted lever having its long arm fixed to said bar, contact means and means engaging the short arm of said lever for operating said contact means in response to 40 partial rotation of said discs.

HOWARD AVERY SATTERLEE.
